DESIGN FOR A STITCH AND SEAM OPENING
DEVICE

Kenly C. Bugg, Fort Wayne, Ind.

Application January 31, 1948, Serial No. 144,191

Term of patent 14 years

(Cl. D3—19)

To all whom it may concern:

Be it known that I, Kenly C. Bugg, a citizen of the United States, residing at Fort Wayne, in the county of Allen and State of Indiana, have invented a new, original, and ornamental Design for a Stitch and Seam Opening Device, of which the following is a specification, reference being had to the accompanying drawing, forming a part thereof:

In the drawing—

Figure 1 is a side elevation of a stitch and seam opening device embodying my new design;

Figure 2 is a side elevation of the stitch and seam opening device illustrated in Figure 1, taken at 90° thereto and looking toward the right as viewed in Figure 1;

Figure 3 is a side elevation of the stitch and seam opening device illustrated in Figure 1, taken at 90° thereto and looking toward the left as viewed in Figure 1; and

Figure 4 is a top plan view of the stitch and seam opening device illustrated in Figure 1.

I claim:

The ornamental design for a stitch and seam opening device substantially as shown.

KENLY C. BUGG.
